FRANK W. MERRICK, OF BOSTON, MASSACHUSETTS

THREAD-CONTROLLING DEVICE FOR SEWING MACHINES

Application filed November 3, 1925. Serial No. 66,501.

The invention has relation in general, to the devices by means of which in sewing machines the needle-thread is controlled. More particularly it relates to needle-thread taking-up means, needle-thread gripping means, needle-thread tension means, and grip and tension-releasing means. It comprises various improvements in connection therewith.

10 An illustrative embodiment of the different features of the invention, constituting a preferred form of embodiment, is shown in the drawings. It will be understood that in practice the construction may be varied more or less.

In the drawings,—

Fig. 1 is a view in side elevation of certain portions of a curved needle sewing machine, including the said illustrative embodiment 20 of the features of the invention, with the exception of the take-up device, which has been omitted therefrom.

Fig. 2 is a partly sectional side elevation showing more particularly the take-up means, and the thread-grip and tension-means, with the devices in positions which relieve the thread from restraint.

Fig. 3 is a view similar to Fig. 2 but including certain parts which are associated with those just named, with the devices in the positions assumed during taking up.

Fig. 4 is a plan view corresponding with Fig. 3.

Fig. 5 is a side elevation illustrating mainly the presser and its controlling mechanism.

Fig. 6 is a similar view illustrating more particularly the presser lock release.

Fig. 7 is a sectional detail.

The features of the invention are shown associated with a machine-frame 1, Fig. 1 (only portions of which are represented) a cam-shaft 2, a curved awl 3, Fig. 1, a swinging awl-carrier 31 and connections through which the awl-carrier and awl are actuated through the rotation of the cam-shaft 2; also an awl-guard 4, a curved needle 5, (only a small portion thereof being represented in Fig. 1), and feed-mechanism. The drawings show also a presser 7, presser-locking and lifting mechanism, a vertically recipro-

cating work-table or support 8 and controlling and operating mechanism therefor, and certain other parts and devices.

A portion of work x is shown in certain of the views of the drawings, in place between the work-table or support 8 and the presser 7. As appears in the drawings, the awl 3 is arranged and actuated to penetrate from above, the work x resting upon the work-table or support and clamped thereto at times by the presser, while the needle 5 is arranged to pass upward into the awl-hole in the work from below, and to draw a loop of the needle-thread y down through the awl-hole. In a lock-stitch machine such loop is caused to pass around the loop-taker or shuttle 6, in order to become interlocked with the under thread. The feeding of the work as successive stitches are made is accomplished in this instance by movement of the awl-carrier and awl in the direction of the feed, while the awl is in the work, such movement being transmitted to them through the feed-lever 395 engaged with a cam-groove in the cam-hub 393 fixed to cam-shaft 2.

A take-up lever is shown at 20, pivotally mounted to swing in a vertical plane around a center at 201, under the actuation of devices which are described later herein. A tension device is shown at 291, Figs. 2, 3 and 4, through which the thread passes between the take-up device and the stitch-forming devices. An adjustable disk tension device of a familiar type is shown, but any suitable form may be substituted in practice. In this instance the take-up lever 20 is shown provided, as common in practice, with two thread-engaging rolls 202, 202, (or they might be simple projections,) arranged for engagement with the needle-thread y at opposite sides (in this instance front and rear) of an intermediately-located roll (or projection) 203 mounted upon a suitable fixed support. The well-known action of a take-up device of this kind is illustrated in Figs. 2 and 3, and may be referred to as follows: In Fig. 2 the take-up lever is in its extreme thread-relieving position; in Fig. 3 it is in its extreme taking-up position. In Fig. 2 the thread y for the time being is free from

the restraint of the rolls or projections 202, 203, and 202, and extends in a straight line between the roll or projection 203 (above) and the rolls or projections 202, 202, (below). In Fig. 3 the thread is so flexed by the three rolls or projections that it is fully drawn back from the work, as in completing and tightening the last formed stitch. As the take-up arm or lever moves from its position in Fig. 3 toward that in Fig. 2 it yields up the thread *y* so as to accommodate the action of the needle in drawing a loop of the thread through the work, and the action of the loop-taker or shuttle in causing the loop to become extended around the loop-taker or shuttle. The tension device 291 serves to maintain the thread under light tension between the take-up device and the stitch-forming devices, as such actions take place, so as thereby to ensure that the loop drawn through the work by the needle shall remain firmly engaged with the hook of the needle, making certain the entrance of the point 60 of the loop-taker or shuttle into the said loop, and also to ensure against accidental release of the loop from the said point.

The first feature of the present invention consists in improved means for actuating a vibrating take-up arm or lever. Such improved means utilizes mechanically advantageous principles for transmission of power to the said arm or lever from a cam or other rotating movement-initiating element, with a dwell of such arm or lever of relatively prolonged duration at the completion of the taking-up movement; also, with the shock which is incident to the strain when the take-up is setting the stitch so absorbed as to save the cam or other movement-initiating element, and the parts engaging therewith, from wear and strain incident to such shock. It provides, still further, for preventing any overthrow of the take-up arm or lever that is permitted by looseness or play in the parts from producing wear of the rotating movement-initiating element and from affecting the amount of thread taken up in a taking-up action.

Referring now to the said actuating means: In the case of the illustrated embodiment of the features of the invention, the hub 204 of the take-up arm or lever 20 is provided with an arm 205, from which a connecting link 206 extends to an arm 207 of a lever that is supported by a rod or shaft 208, a second arm, 209, of said lever being provided with a cam-follower 210 working in a cam-groove 211 in a cam-disk 212 fixed upon cam-shaft 2. Cam-disk 212, with its cam-groove 211, constitutes a movement-initiating member such as aforesaid. The connecting link 206, included as just explained in the actuating train for the take-up arm or lever, is combined with the lever arms 207 and 205 in relations enabling it to cooperate as a toggle-

link with such arms in completing a taking-up movement of the take-up arm or lever. In the operation of the mechanism the movement-initiating cam acts through the associated elements of the said train to move the take-up arm or lever at one time into the thread-relieving position of Fig. 2, and then from the said position toward and into the position in Fig. 3 in which taking-up has been accomplished, and then from the position of Fig. 3 to that of Fig. 2, and so on.

As the actuating cam actuates the lever 209, 207, from its position in Fig. 2 toward its position in Fig. 3, the arm 207 acts through link 206 to push the rear arm 205 of the take-up arm or lever downward in the drawings, rocking the take-up arm or lever so that the thread-engaging elements 202, 202, are carried past and beyond the intermediate element 203, with flexing of the thread around the three elements as in Fig. 3, and corresponding taking-up action. In this latter actuation of the parts the point 213 of pivotal connection between arm 207 and link 206 is carried toward a line extending from the axis of lever 209, 207, to the point of connection, 214, between such link and the arm 205 of the take-up arm or lever. This approach of said point 213 toward and approximately to the said line, or it may be carried slightly past such line, produces a toggle-action in occasioning the taking-up stroke of the take-up arm or lever. Such toggle-action gives the requisite power for the actuation of the parts in the taking-up action, without injurious strain upon the lever 209, 207, and without causing undue wear upon the actuating cam.

Other advantages are secured through constructing the mechanism so that in the taking-up action the joint at 213 between the lever-arm 207 and the link 206 moves toward and into a position more or less approximately in a straight line with the centers at 208 and 214. By reason thereof the strain which is incident to overcoming the resistance offered by the thread as the tightening of the last formed stitch nears completion is transmitted along the more or less approximately straight line extending between point 214 and the rod or shaft 208, so that such strain is absorbed by the said rod or shaft and its bearings, without reaching the cam through the power-receiving arm 209 and the cam-follower. This relieves the cam and cam-follower from the shock and from the action which in the case of prior mechanisms cause excessive wear and deformation of that portion of the cam which is in play during the period of greater resistance.

Another important result is that overthrow of the take-up arm or lever at the conclusion of its taking-up movement, due to momentum acquired by such arm during such movement, is practically eliminated by reason of the fact that such momentum of the

said arm or lever acts in a direct line between pivotal point 214 and the rod or shaft 208 and in consequence is almost completely absorbed by the said rod or shaft and its bearings, so that there is practically no tendency to springing of lever 209, 207, or to sudden movement, by reason of such momentum, of the cam-follower 210 across the cam-groove into forcible contact with the wall of such groove at a point opposite the throw-point of the cam-groove, with resulting wear of such wall at the point of contact and resulting looseness and play of the cam-follower within the groove. The avoidance of wear of the cam-groove at the said opposite point averts the increasing overthrow of the take-up arm that would result from such wear.

Heretofore in practice a thread-grip has been employed for engagement with the needle thread closely adjacent the take-up device, between the latter and the source of thread-supply, to prevent thread from being drawn from the source of supply by the take-up device in taking up, in order thereby to ensure that such thread as is taken up by the take-up device in completing a stitch shall consist solely of what is drawn back through the work. Certain of the features of the present invention are associated with thread-gripping means of this class. Accordingly, the drawings show, more particularly in Figs. 1 to 4, at the supply-side of the thread taking-up elements a device which, as heretofore in some instances, and as I prefer in practice, is thread-operated to grip the thread *y* at the said side of the said elements, in order to ensure the result just specified, namely that such thread as is taken up by the action of the take-up device shall consist solely of what is drawn back through the work. In the form shown herein this device comprises, as heretofore in some instances, a lever 301 which is mounted pivotally at 302 upon a stationary part of machine-frame 1, and a surface 303 adjacent the heel 304 (Fig. 3) of said lever, between which surface and the said heel the thread *y* passes on its way from the source of supply, and then extends lengthwise of the long arm of the lever, within a downwardly-opening groove in the underside of said long arm. As heretofore, when the take-up arm is actuated to take up the thread, that portion of the thread which engages with the long arm of the gripping lever, and which partakes of the swinging movement of the take-up arm or lever, actuates the said gripping lever so that the gripping lever turns on its fulcrum or pivot, causing the thread to be clamped between the lever-heel and the opposing surface 303. Sometimes in practice, in the use of devices of this class, the thread renders so freely from the supply-side of the gripping lever that

ing-up movement of the take-up lever it does not exert sufficient force thereagainst to cause the heel of the gripping lever to grip and hold the thread, at first, from which it results that the thread-gripping action is delayed, so that during the first portion of the taking-up movement of the take-up lever the thread is still free to render forward from the supply-side past the gripping point. Consequently, the taking-up action is incomplete and imperfect, and the stitch-interlock is not drawn the proper distance into the thickness of the work *x*. In order to remedy this fault, I find it advisable to provide for yielding actuation of the gripping lever so that when the taking-up action begins there shall be pressure of the lever-heel against the surface 303 and the thread intervening between them. The result of this pressure is that the lever-heel acts as one member of a tension-device whereby any movement of the thread onward between the lever-heel and the surface 303 is resisted, from which it follows that any forward pull on the thread acting at a point beyond the lever fulcrum or pivot produces a tension in the thread. This tension renders the thread effective, as the take-up lever moves from its position in Fig. 2 to its position in Fig. 3, carrying the more or less taut thread with it, to act instantly to actuate the gripping-lever to clamp the thread effectually between the lever-heel and the opposing surface 303. By reason of this clamping promptly at the beginning of the taking-up action, no portion of the thread can render past the point at which it is arranged that clamping of the thread shall take place.

In this instance, for the yielding actuation of the grip-device to cause it to take a frictional hold upon the thread, I employ an expanding spiral spring 324, the tension of which acts with a tendency to move endwise a rod 305 that is engaged with an ear 306 with which the gripping-lever is provided. Thus the spring tends to close together the jaws of the thread-gripping device. The rod passes through a guide 307, Fig. 3, in connection with a fixed part of the machine-frame 1, the spring being mounted upon the rod behind the back of the said guide, and being confined between such guide and a nut 308 upon the screw-threaded end of the rod, 309 being a lock-nut that is associated with nut 308. By adjustment of the said nuts the spring-tension may be regulated so as to vary the pressure of the gripping-lever heel upon the thread and thereby secure the desired degree of tension in the thread as it is drawn forward through the tension device; in other words, thereby secure the desired stitch-forming tension. The relations and the mode of operation will be clearly apparent from Fig. 3 of the drawings.

In order to relieve automatically the ef-

fect of the tension-device upon the thread at certain times in the working of the machine, relief devices are provided, comprising in this instance a lever 310 and a cam 311, Figs. 2 and 3. Such cam is carried by one, 312, of the cam-hubs upon cam-shaft 2. The cam actuates the lever to move the rod 305 to swing the gripping-lever so as to relieve the pressure of its heel upon the 10 thread between such heel and the opposing surface 303. To provide for varying the extent to which the said heel is separated from the said surface through the action of the cam, the lever actuates the rod 305 15 through the intervention of a contact screw 313 that is carried by the lever and acts against one rod-end. Through adjustment of the screw 313 so as to vary the amount of lost motion between the screw and the 20 end of the rod, the required variation in the extent of the opening movement may be secured, so as to suit different sizes of thread. A lock-nut 314 is shown in connection with the screw 313, to prevent accidental loss of adjustment.

In the operation of the machine in which the foregoing devices are employed, the cam 311 actuates the thread-grip so as to release the thread and thereby relieve the tension 30 of the thread partially during the greater part of that portion of the movement of the loop-taker or shuttle by which the loop of thread that has been engaged thereby is extended to almost the full diameter of 35 the loop-taker or shuttle. During such period of relief the thread draws readily from the source of supply. Hence, excessive strain by such thread upon the material being stitched during the extension of the 40 loop to pass around the loop-taker or shuttle is obviated. Just before the loop-taker or shuttle has drawn the loop of thread to its fullest size, that is to say, just before the loop that has been engaged by the point or 45 tip of the loop-taker or shuttle is extended around the full diameter of the loop-taker or shuttle, the tension device is permitted to act. In other words, the spring 324 is 50 permitted to close the heel of the thread-gripping lever upon the thread at such time so as to oppose the free advancing movement of the thread. This preliminary closing of the thread-gripping lever through the action of spring 324 takes place before 55 the taking-up action begins. By reason of such time-relation, the gripping lever by its closing upon the thread in advance of the taking-up action operates to prevent any 60 stealing of thread from the supply-side of the devices at the beginning of the taking-up action, as a result of slipping of the thread past such lever. Next the take-up 65 operates, and as it acts the thread being thereby given increased tension, the pull of 70 the thread by the take-up against the long

arm of lever 301 as in Fig. 3 causes the thread-grip to function so as to prevent any thread from being drawn by the take-up from the source of supply as the loop aforesaid is taken up and the stitch is tightened. 70 So far as concerns the operation of tightening a stitch the take-up operates upon only the amount of thread that the shuttle determined to be necessary in making the 75 stitch. In virtue of the employment of means independent of the take-up device, such means constituted in this instance by cam 311 and lever 310, for controlling the thread-gripping lever independently of the movements of the take-up lever, I am enabled to time the preliminary closing of the 80 thread-gripping lever, and also the subsequent opening of the same for partial relief of the tension, independently of such movements, and thus to secure more advantageous results in the stitch-forming operations.

If the wax employed in the wax-pot partly shown at W should be a little cold, the thread will drag in being pulled forward from the source of supply. Or some other cause may operate to the same effect. This might unduly tighten the stitch. To guard against this a thread pull-off is provided between the take-up device and the source of supply. In this instance such pull-off comprises a thread-engaging projection 9 moving with the take-up lever, and a fixed rest 91 over which the needle-thread draws at the rear of said projection. The thread passes from said rest 91 under the pull-off projection 9 to and through a guide 92 behind the thread-grip. In the thread-relieving position of the take-up device the pull-off projection 9 is elevated sufficiently to permit the thread to extend in an approximately direct course from rest 91 to guide 92, as shown in Fig. 2, but as the take-up moves to its complete taking-up position, operating to close the thread-grip more firmly upon the thread, the pull-off projection also operates to flex or bend the thread more fully, as in Fig. 3. Inasmuch as at the time when this action takes place the thread is gripped by the grip-device, so that the thread cannot be drawn back through the take-up device, 100 this flexing of the thread operates to draw forward from the direction of the source of supply the additional amount of thread that is required for use in the production of the 105 next ensuing stitch.

For the purpose of releasing the pressure of the heel of the thread-gripping device upon the thread, simultaneously with manually performed unlocking of the presser and lifting of the presser, I provide a release lever 80, shown best in Fig. 1, having an upwardly-extending arm 81 disposed properly for engagement with a collar 82 upon rod 305. The downwardly-extending arm of the said lever is so related to a projection 83 in con- 110

nection with a rod 15 extending to a pedal, hand-lever, or the like, that when rod 15 is moved by the machine operator in the proper direction to relieve the presser-lock and lift the presser, the said projection acts against said downwardly-extending arm and thereby actuates lever 80 to cause the latter, through engagement with collar 82, to move rod 305 to swing the thread-grip lever so as to relieve the engagement of its heel with the thread.

The connection of the manually actuated rod 15 with presser unlocking and presser lifting means is illustrated in Figs. 1, 5, and 6. In the said views the presser-carrier 71 is shown mounted to rock upon an axis at 72 and actuated by means of a spring 73 for the purpose of moving the presser toward the work table or support 8 and causing the presser to cooperate with the work table or support in clamping the work α during the penetration of the work by the awl 3, etc. The presser-locking means shown in the drawings comprises a pivoted locking dog 10, arranged to act in conjunction with a segment 101 carried by the presser-carrier, a spring 102 being arranged to act upon the locking dog 10 so as to cause it normally to grip the segment 101 and prevent the presser from moving farther away from the work table or support. It is usual to employ devices acting during the working of the machine for automatically releasing the presser-grip or lock so as to leave the presser free to be lifted to provide for each feed movement. The drawings show a release cam 103, Figs. 5 and 7, fixed upon a rockshaft 11 mounted in the upper portion of the machine frame. This rockshaft is rocked prior to each feed movement through suitable connections with a cam on cam-shaft 2. The drawings show also means for automatically lifting the presser after it has been unlocked, such means including a lifting tappet 12, Figs. 1 and 5, fixed upon the rockshaft 11 and acting in conjunction with a well-known form of lifting clamp arrangement, represented in Figs. 1 and 5, but unnecessary to be described.

The manual unlocking of the presser is provided for in the case of this embodiment of the invention by means of a second grip release cam, 14, Figs. 6 and 7, mounted loosely upon rockshaft 11 in position to act upon grip-lever 10, said cam 14 having an arm 141 with which is engaged the upper end of the rod 15. For the purpose of enabling the presser to be manually lifted, in addition to being manually unlocked as just explained, an arm 16, with which the rod 15 is connected also, is articulated with the presser-carrier by a pivotal joint at 161, the said arm having a finger 162 which projects down alongside the lower portion of the presser-carrier. The construction permits the automatically produced lifting and lowering of the presser to take place without being interfered with by

the arm 16, but provides that as the rod 15 is moved downward for the purpose of rocking the release cam 14 to effect manual unlocking of the presser, the finger 162 shall make contact with the presser-carrier and rock the presser-carrier in the proper direction to lift the presser.

What I claim as the invention is:—

1. Take-up mechanism comprising a take-up arm or lever, a rotating movement-initiating element, a lever actuated by said element, and a link through which movement is transmitted from said lever to said take-up arm or lever, with said link cooperating with said parts as a toggle-link which, as the mechanism completes the taking-up stroke of the take-up arm or lever, approaches and assumes a dwell-relation in which its effective length is substantially in line with the center on which the said lever swings.

2. Take-up mechanism comprising a take-up arm or lever, a rotating movement-initiating cam, a lever engaged by said cam and actuated thereby to produce taking-up movement of the take-up arm or lever, and a link co-operating with said parts at a toggle-link which, as the mechanism completes the taking-up stroke of the take-up arm or lever, approaches and assumes a dwell-relation in which its effective length is substantially in line with the center on which the said lever swings.

3. Take-up mechanism comprising a take-up arm or lever, a lever, means for vibrating said lever to thereby cause the same to actuate the take-up lever, and a link pivoted at one end to an arm of the take-up lever and pivoted at the other end to an arm of the actuating lever, with the parts related so that in the final stage of the taking-up action the second pivot becomes intermediately aligned with the first pivot and the pivotal axis of the actuating lever whereby the reversely acting strain and reaction occurring in the said final stage are absorbed by the pivotal mounting of the actuating lever without reaching the means for vibrating such lever.

4. Take-up mechanism comprising a take-up arm or lever, a lever, means for vibrating said lever to thereby cause the same to actuate the take-up lever, and a link pivoted at one end to an arm of the take-up lever and pivoted at the other end to an arm of the actuating lever, with the parts so related that at the completion of the intended travel of the take-up lever in the taking-up action the effective length of the link is in alignment with the connected arm of the actuating lever, so that overthrow of the take-up lever is resisted by the pivotal mounting of the actuating lever without being transmitted to the means for vibrating such lever.

5. Take-up mechanism comprising a take-up lever, an actuating grooved cam, an intermediate lever having a cam-follower work-

ing in the cam-groove of such cam, and a link pivoted at one end to an arm of the take-up lever and pivoted at the other end to an arm of the intermediate lever, with the parts related so that at the conclusion of the taking-up action the second pivot moves into alignment with the first pivot and the pivotal axis of the intermediate lever, intermediately thereof, whereby the shock and strain resulting from overthrow of the take-up lever are absorbed by the pivotal mounting of the intermediate lever without reaching the cam.

6. The combination comprising a take-up device, a device at the supply-side thereof which is thread-actuated to grip the thread during the taking-up action, and which normally creates tension in the thread whereby promptness in the gripping action is secured, and means independent of the said take-up device whereby the tension-producing action is relieved as well as instituted independently of the movements of the take-up device.

7. The combination comprising a take-up device, a device at the supply-side thereof which is thread-actuated to grip the thread during the taking-up action and which normally creates tension in the thread whereby promptness in the gripping action is secured, and means independent of the said take-up device whereby said combined grip and tension device is actuated intermittently independently of the movements of the take-up device to apply and to relieve the tension as the needle-thread is drawn through the work in a stitch-forming operation.

8. The combination comprising a take-up device, a device at the supply-side thereof which is thread-actuated to grip the thread during the taking-up action and which normally creates tension in the thread whereby promptness in the gripping action is secured, and manually controlled means whereby at the will of the operator said combined grip and tension device may be actuated to relieve the tension so as to permit the thread to be drawn onward.

9. The combination comprising a work-presser, a take-up, a combination thread-tensioning device and thread-actuated thread-grip at the supply-side of said take-up device, and manually-controlled means for conjointly raising the work-presser and actuating said combination device to relieve the tension so as to permit the thread to be drawn onward.

10. The combination comprising a take-up device, a thread-actuated thread-grip at the supply-side of said device, a spring coacting with said thread-grip to cause it to act normally as a thread-tensioning device, and means independent of the said take-up device acting intermittently in opposition to said spring independently of the movements of the take-up device to release the thread and permit it to render freely past the combina-

tion grip and tension device in a stitch-forming operation.

11. The combination comprising a take-up device, a thread-actuated thread-grip device at the supply-side of said device, a spring coacting with said thread-grip device to cause it to act normally as a thread-tensioning device, and manually-controlled means whereby at the will of the operator said thread-grip device may be actuated to release the thread and permit it to be drawn freely past such device.

12. The combination comprising a take-up device, means at the supply-side of such device actuated by the thread in a taking-up action to grip the thread for such action and at other times actuated by a spring to create tension in the thread, and means independent of the said take-up device acting intermittently independently of the movements of the take-up device in opposition to said spring to release the thread and permit it to render past the combination grip and tension means in a stitch-forming operation.

13. The combination comprising a take-up device, a thread-actuated thread-grip at the supply-side of said device, a spring coacting with said thread-grip to cause it to act normally as a thread-tensioning means, and a cam acting intermittently through connecting means independent of said take-up device to release the thread and permit it to render past the combination grip and tension device in a stitch-forming operation.

14. The combination comprising take-up means, a thread-actuated thread-grip device at the supply-side of said means also acting normally as a thread-tensioning means, and a cam and connecting means independent of said take-up means by which intermittently said device is caused to release the thread to permit it to render past the same in a stitch-forming operation.

15. The combination comprising take-up means, a thread-actuated thread-grip device at the supply-side of said means also acting normally as a thread-tensioning means, a cam by which intermittently said device is caused to release the thread to permit it to render past the same in a stitch-forming operation, and means for manually controlling the said device to release the thread at the will of the operator.

16. The combination comprising take-up means, a thread-actuated thread-grip member at the supply-side of said means, a rod connected with said member, a spring by which said member is caused to act normally as a tensioning device, and an actuating cam and lever acting through said rod to release the thread intermittently to permit it to render past said member in a stitch-forming operation.

17. The combination comprising take-up means, a thread-actuated thread-grip mem-

ber at the supply-side of said means, a rod connected with said member, a spring by which said member is caused to act normally as a tensioning device, an actuating cam and lever acting through said rod to release the thread intermittently to permit it to render past said member in a stitch-forming operation, and means for manual actuation through said rod to effect release of the thread at the will of the operator.

18. The combination comprising take-up means, a thread-actuated thread-gripping lever at the supply-side of the take-up means, a spring by which said lever is actuated to cause it to act by pressure upon the thread as a thread-tensioning means, a cam, and a lever independent of said take-up means by which said thread-gripping lever is actuated to release and relieve the thread, and adjustment means for varying the extent of the relief-movement imparted to the thread-gripping lever.

19. A sewing machine having a loop-taker or shuttle provided with a point or tip which in the action of the loop-taker or shuttle engages the loop of thread that has been drawn by the needle through the work and extends such loop around the loop-taker or shuttle, a take-up device, a device at the supply-side thereof which is thread-actuated to grip the thread during the taking-up action and which normally creates tension in the thread whereby promptness in the gripping action is secured, and means whereby the tension-producing action is relieved during the extension of the loop around the loop-taker or shuttle until shortly before arrival of the loop at the full diameter of the loop-taker or shuttle, and then such action is permitted to take effect.

20. A sewing machine having a loop-taker or shuttle provided with a point or tip which in the action of the loop-taker or shuttle engages the loop of thread that has been drawn by the needle through the work and extends such loop around the loop-taker or shuttle, a take-up device, a device at the supply side thereof which is thread-actuated to grip the thread during the taking-up action and which normally creates tension in the thread whereby promptness in the gripping action is secured, and means independent of the said take-up device whereby the tension-producing action is relieved during the extension of the loop around the loop-taker or shuttle until shortly before arrival of the loop at the full diameter of the loop-taker or shuttle and then such action is permitted to take effect.

21. A sewing machine having a loop-taker or shuttle provided with a point or tip which in the action of the loop-taker or shuttle engages the loop of thread that has been drawn by the needle through the work and extends such loop around the loop-taker or

shuttle, a take-up device, means at the supply-side thereof which is actuated by the thread in a taking-up action to grip the thread for such action and at other times actuated by a spring to create tension in the thread whereby promptness in the gripping action is secured, and means whereby the tension-producing action is relieved during the extension of the loop around the loop-taker or shuttle until shortly before arrival of the loop at the full diameter of the loop-taker or shuttle, and then such action is permitted to take effect.
